FLUORESCENT LAMP CIRCUIT

Lester J. Nevills, Lemay, Mo., assignor of one-half to Stupp Bros. Bridge & Iron Company, St. Louis, Mo., a corporation of Missouri

Application October 16, 1947, Serial No. 780,195

11 Claims. (Cl. 315—97)

1

This invention relates to control circuits and in its more specific aspects is directed to a control circuit for fluorescent light fixtures.

The object of this invention is to provide a control circuit for fluorescent light fixtures wherein a single timing unit will control the lighting of a plurality of light fixtures.

Another object of the invention is to provide a control circuit in which one time delay relay circuit will control the disconnection of the heating elements for the several fluorescent fixtures and in which the time for the delay relay's operation may be varied to suit individual fixture requirements.

In the drawings:

Fig. 1 is a circuit diagram incorporating the invention,

Fig. 2 is an elevational view of a portion of a switch control panel; and

Fig. 3 is a section view taken along the line 3—3 of Fig. 2.

Referring now to the drawings, numeral 1 designates a transformer which is excited from a suitable source of current of preferably 220 volts, indicated generally by conductors 2 and 3 for the circuit beginning with conductors 4 and 5 through switches 6 and 7 which may be of any suitable type.

The timing mechanism for the control circuit consists of a relay 8 and a rectifier tube 9, the rectifier filament being heated from a secondary winding on transformer 1, with the rate of heating being controlled by a rheostat 10. The output side of the plate circuit for the rectifier is connected to the electromagnet of the relay 8 in the customary manner. The armature for the relay 8 opens and closes a switch 11 in the circuit for the panel switch operating solenoid 12. The armature 13 for solenoid 12 is mechanically connected to a panel switching member 14 by linkage 15. The member 14 has a strip of insulation 14' secured thereto, all of which extends the full length of the panel board 16. The panel board is only schematically illustrated in Fig. 1 but is more completely detailed in Figs. 2 and 3.

A plurality of switch blades 17, 17', etc., are rigidly mounted on but insulated from the panel 16 by suitable securing means and a plurality of fixed switch contacts 18 (only one of which is shown) is secured to the panel. A member 19 is laid across the upper end of the blades to assist in keeping them in position. A plurality of fixed contacts 20 equal in number to contacts 18, is also mounted in the panel board and fixtures 21

are connected between each set of contacts 18 and 20.

Contact 20 extends through the panel board 16 and is engageable with a movable contact 22 mounted on switch blade 17. Contacts 22 and 20 are separated by solenoid armature 13 through linkage connection 15 and a suitable spring (not shown) customary in the art may be employed to return solenoid 13 to inoperative position.

An auto or ballast transformer 23 is connected across conductors 4 and 5 in the manner illustrated by conductors 24 and 25. The lamp bulbs 21, 21 are each provided with starting heating elements 26, 27 and 28, 29, respectively. The starting circuit for heating elements 26 and 27 consists of conductors 30, 31 heating element 26, conductor 32, contacts 20, 22, switch blade 17, contact 18, conductor 36, heating element 27, and conductor 35 to the transformer. The circuit for heating elements 28 and 29 consists of conductor 30, heating element 28, conductor 33, contact 18, blade 17', contacts 20, 22, conductor 37, heating element 29, and a conductor 34 to the transformer.

These circuits remain closed until the starting elements have been sufficiently heated, the time therefor being determined by the rheostat for the delay relay 8, previously described. When relay 8 closes switch 11, solenoid 12 is energized, whereupon contacts 22 and 20 (Fig. 3) separate to thereby impose a potential across respective heating elements 26, 27 and 28, 29 or across the entire fixture to keep the fluorescent bulbs 21, 21 charged and illuminated as long as this potential is maintained, the heating elements functioning as electrodes during normal illumination of bulbs 21, 21.

Switch blades 17'' and 17''' are not shown connected to any fixtures but by the provision of another ballast or auto transformer, additional light fixtures may be connected to the panel board contacts associated with blades 17'' and 17''' in the manner just described. Any number of lamp bulbs 21, 21 may be connected to a single panel board and all may be controlled by a single time delay relay 8. The connection described has been found to be very reliable under various temperature conditions working equally well in cold as well as in very warm temperatures. Flickering of lights has also been eliminated because each heating unit is subjected to constant and unvarying conditions, starting time has been shortened and illumination improved with the above described circuit.

What I claim is:

1. A control circuit for a plurality of light fixtures comprising a transformer; a pair of light bulbs having a pair of heating elements in each bulb; a switch panel having a plurality of pairs of switch blades thereon; circuit means to connect the heating elements in each lamp, the switch blades and the transformer so that there is a separate circuit for each lamp and one of said blades; a relay to simultaneously actuate said switch blades to disconnect said elements and to simultaneously impose a voltage across each of said lamps; and a time delay mechanism to operate said relay.

2. A control circuit for a plurality of light fixtures comprising a transformer; a plurality of pairs of light bulbs; a pair of heating elements in each bulb; means to connect the heating elements for each lamp into a circuit with said transformer and impose a voltage across each element; a panel having a plurality of switch means thereon with one switch means in each circuit to open same to thereby impose a voltage across each lamp; means to operate said switch; and means to operate said last mentioned means a predetermined time after said circuit is closed.

3. A control circuit for a plurality of light fixtures comprising a transformer; a light bulb having a pair of heating elements therein; means to connect said heating elements to said transformer to impose a voltage across each element; means to open said circuit and to simultaneously impose a voltage across said bulb; a relay to operate said last mentioned means; and means to operate said relay a predetermined time after said first mentioned means is operative.

4. A control circuit for a plurality of light bulbs in which each bulb is separately controlled comprising a panel board provided with a plurality of switch blades and to which a plurality of bulbs is connected; each bulb provided with a pair of heating elements; a circuit for each bulb which includes both of said heating elements and one of said blades; a transformer to which said circuit is connected; a switch in said circuit to control same and to simultaneously impose a voltage across each bulb connected to said panel; and means to open said switches a predetermined time after said circuit is closed to thereby impose a voltage across each bulb.

5. A control circuit for a plurality of light bulbs in which each bulb is separately controlled comprising a panel board provided with a plurality of switches to which a plurality of bulbs is connected; each bulb provided with a pair of heating elements; a circuit to connect the heating elements for each bulb and one of said switches in series; a transformer to which said circuit is connected; a relay to close said circuit to thereby connect said heating elements in each bulb and one of said blades in series; means to simultaneously open said switches a predetermined time after said circuit is closed by said relay to thereby impose a voltage across each bulb; and means to vary the time said circuit is closed.

6. A control circuit for fluorescent light bulbs, each provided with a pair of heating elements, comprising a transformer connected to a voltage source; circuit means to connect said transformer to said heating elements while connected in series

in order to heat same; a switch in said circuit; and means to open said circuit after it has been closed a predetermined length of time, said circuit being then arranged so that said voltage is imposed across the light bulbs to energize the bulbs.

7. A control circuit for fluorescent light bulbs, each provided with a pair of heating elements, comprising circuit means to connect said heating elements in series in order to heat same; a transformer to which said circuit is connected in order to energize same; a switch in said circuit; and means to open said switch after it has been closed a predetermined length of time, said circuit being then arranged so that a voltage is imposed across the light bulbs to energize the bulbs.

15. 8. A fluorescent light circuit switch operating mechanism comprising a transformer; a rectifier connected thereto; a relay operable by current derived from said rectifier; a switch panel having a plurality of switch elements thereon connectable in a light circuit; and means for simultaneously operating each of said switch elements controlled by said relay.

20. 9. A fluorescent light circuit switch operating mechanism comprising a transformer; a rectifier connected to said transformer; a relay operable by current derived from said rectifier; a switch 30 panel having a plurality of switch blades thereon connectable in lamp circuits; a solenoid for simultaneously operating each of said switch blades and controlled by said relay; and means for varying the time required for the operation of said 35 relay.

25. 10. A fluorescent light circuit switch operating mechanism comprising an alternating current supply; a transformer connected to said supply; a rectifier connected to said transformer; a relay including a switching member and operated by current derived from said rectifier; a switch panel having a plurality of simultaneously operated switch elements thereon; a solenoid for simultaneously operating the switch elements on said 40 panel; a circuit for said solenoid which includes the switching member on said relay and connectable to said source of supply when said relay is operated; and means for varying the operating time of said relay.

45. 11. A fluorescent light circuit switch operating mechanism comprising a switch panel having a plurality of switch blades thereon; a solenoid for simultaneously operating each of said switch blades; a relay for controlling the operation of said solenoid; means for energizing said relay; and means for regulating the time required for energizing said relay.
